United States Patent Office

Des. 178,941
Patented Oct. 9, 1956

178,941

GAME BOARD OR THE LIKE

John W. Warrick, Plainview, Tex.

Application April 23, 1956, Serial No. 41,165

Term of patent 7 years

(Cl. D34—5)

Fig. 2.

I claim:

The ornamental design for a game board or the like, substantially as shown.
